CLAIM

The ornamental design for a device holder, as shown and described.

DESCRIPTION

FIG. 1 is a front, top, side perspective view of a device holder, showing my new design in an environment of use with a device;

FIG. 2 is a front, top, side perspective view of the device holder of FIG. 1;

FIG. 3 is a front elevation view thereof;

FIG. 4 is a back elevation view thereof;

FIG. 5 is a top plan view thereof;

FIG. 6 is a left side elevation view thereof;

FIG. 7 is a right side elevation view of thereof, showing the device holder of FIG. 1 in another environment of use with two devices;

FIG. 8 is a right side elevation view of the thereof; and, FIG. 9 is a bottom plan view thereof.

The broken lines are for the purpose of illustrating the environment of the article only and form no part of the claimed design.
